UNITED STATES PATENT OFFICE.

AUGUST WILLENBACHER, OF HACKENSACK, NEW JERSEY, ASSIGNOR TO ROYAL ART GLASS COMPANY, OF NEW YORK, N. Y., A CORPORATION OF NEW YORK.

DESIGN FOR A LAMP-SHADE-BRACKET PIECE.

53,622.

Specification for Design.

Patented July 15, 1919.

Application filed March 11, 1919. Serial No. 282,044. Term of patent 3½ years.

To all whom it may concern:

Be it known that I, AUGUST WILLENBACHER, a citizen of Germany, and resident of Hackensack, in the county of Bergen and State of New Jersey, have invented a new, original, and ornamental Design for a Lamp-Shade-Bracket Piece, of which the following is a specification, reference being had to the accompanying drawing, forming part thereof.

An embodiment of my new design for a lamp shade bracket piece is shown in the accompanying drawing, in which—

Figure 1 represents a top plan view of the bracket piece,

Fig. 2 represents a side elevation of the same, and

Copies of this patent may be obtained for five cents each, by addressing the "Commissioner of Patents, Washington, D. C."

Fig. 3 represents a bottom plan view of the same.

The design comprises the collar 1 having upwardly curved arms 2 radiating therefrom the free ends of the said arms terminating in slightly enlarged cylindrical sockets 3.

I claim:

The ornamental design for a lamp shade bracket piece, substantially as shown and described.

AUGUST WILLENBACHER.
